PROCESS FOR THE DEWAXING OF OILS

Alfred Hoppe and Hermann Franz, Frankfurt am Main, Germany, assignors to Edeleanu Gesellschaft m.b.H., Frankfurt am Main, Germany

Application November 21, 1955, Serial No. 548,227

Claims priority, application Germany November 26, 1954

4 Claims. (Cl. 208—25)

The present invention relates to a continuous process for the removal of aliphatic compounds such as paraffinic waxes from hydrocarbon oils.

Extensive experimentation has established that urea forms solid compounds or adducts with straight-chain paraffin hydrocarbons. Derivatives of the straight-chain paraffins, for instance olefins, oxygen, nitrogen, sulfur and halogen-containing substances, will similarly enter into this reaction with urea, provided that they do not contain long side chains.

While urea $\text{CO}(\text{NH}_2)_2$ forms adducts with straight-chain paraffins and their derivatives, thiourea $\text{CS}(\text{NH}_2)_2$ forms adducts with branched-chain paraffins and naphthenes under conditions similar to those for adduct formation between urea and n-paraffins.

In order to produce the adducts, the liquid paraffins or their derivatives are brought into contact with urea; the solid adduct produced is separated from the non-adduct forming substances and (1) by heating to elevated temperatures or (2) by the addition of solvents is reconverted into paraffins on the one hand and (1) the urea or (2) a solution thereof on the other hand. The paraffins form the one final product and the non-adduct-forming substances the other final product; the urea or thiourea solution is used again for further formation of adduct. The temperature of the adduct formation depends upon the size of the molecules of the hydrocarbons and is generally between -10 and $+50^\circ\text{C}$. The quantity of urea to be used also differs; it increases with the length of the chains and is an average of 3 parts by weight of urea to 1 part by weight of paraffin. The commencement and duration of the adduct formation is activated by the presence of solvents for the urea. As such, there may be used water and/or water-miscible solvents, e.g. lower alcohols such as methanol and ethanol, ketones such as acetone, and the like. The quantity of the solvent, the so-called activator, varies within wide limits since the urea may be used as a saturated or supersaturated solution or as a paste wetted with solvent. Viscous and paraffin-rich oils are diluted with solvents which have a good dissolving power for the oil to be treated—but not for the adduct—such as benzene, naphtha, organic halogen compounds, and the like.

For the sake of brevity, as used hereinafter, the removal of paraffins or dewaxing embraces both the formation of an adduct of urea with n-paraffins or their derivatives, and of thiourea with isoparaffins, naphthenes or their derivatives.

The speed with which the adduct is formed, as well as the quantity of paraffin taken up through formation of the adduct, is also dependent upon the quantity of the adduct former available. Assuming that it is desired to remove a predetermined amount of paraffinic hydrocarbons or waxes from an oil to bring the pour point to a predetermined value, there would be employed three times as much urea by weight as contrasted with the paraffin. Completion of the reaction would require

extremely long contact periods which would make a continuous process impractical.

The major portion of the paraffins or waxes readily enters into adduct formation. The balance of the paraffinic materials, often as low as 5% of the total paraffinic content, requires several hours and often several days until it is completely combined as an adduct.

The lower the pour point of an oil, the greater will be the influence exerted on such pour point even by 10 small quantities of waxes of paraffinic nature. Thus, for instance, the presence of 1% paraffin has an insignificant effect on the pour point of an oil when the pour point is 10°C , for instance. However, the same quantity of paraffinic wax increases the pour point several degrees 15 when the pour point of the oil is between -15°C and -20°C . It is therefore necessary that the paraffin content be reduced to a predetermined level in order to obtain the desired pour point, and commercial necessity requires that this is effected in a minimum amount of 20 time.

To this end it is possible to add the urea in excess of the quantity theoretically required for adduct formation with all the paraffin to be removed. The reaction under such conditions will be terminated at such time 25 as it is calculated will be required for the predetermined quantity of paraffin to be combined through adduct formation. It is clear that at this time, however, not all of the urea will have entered into adduct formation and thus will pass through the process unchanged. The 30 overall effect is to reduce the amount of oil which can be treated in equipment of a given volume, to increase the cost of urea for a given dewaxing operation, and otherwise to increase the cost of obtaining oil of the desired pour point.

In accordance with the present invention these disadvantages are avoided and overcome, the novel process being rapidly conducted without the use of excess urea. The urea or thiourea is contacted with the paraffin-containing oil in stages, i.e., in the first stage untreated 40 oil is contacted with an adduct still containing some uncombined urea. In the final stage, the pre-treated oil is contacted with fresh urea or regenerated urea respectively, the products constituting the oil of desired pour point and an adduct phase containing uncombined urea which is sent to the first stage for reaction with fresh oil.

In this manner, in the first stage the free urea still present in the adduct is rapidly combined with those components of the untreated oil which have the greatest 45 tendency to form adducts. In the final stage, the oil from which the most reactive components have been removed is contacted with fresh urea in excess of the quantity required to remove the remaining paraffins from the oil. As a result the paraffins are taken up quickly and the excess urea serves for the pre-treatment of further oil.

The invention will now be described with reference to the accompanying drawings, wherein:

Figure 1 is a flow-sheet of a process conducted without temperature control; and

Figure 2 is a flow-sheet of a modified process conducted with individual temperature control during the separate stages of the reaction.

Referring now to the process described schematically in Fig. 1, an adduct of urea with straight-chain paraffins or their derivatives and containing unreacted urea is 65 passed from filter 10 through conduit 11 into mixer 12. Fresh oil, containing straight-chain paraffinic waxes which it is desired to remove, is introduced through conduit 13 into the mixer 12 where it is permitted to contact the unreacted urea carried along with the adduct and introduced through conduit 11. The paraffinic compounds having the greatest affinity for the urea form

adducts with the urea until the urea is completely exhausted through adduct formation.

The suspension of adduct and oil still containing some paraffinic materials, is passed through conduit 14 into a centrifuge 15 where the oil is separated from the solid adduct. The adduct is preferably passed through washer 16 and then to the decomposer 17 where upon addition of urea solvent through conduit 27 it is broken down into paraffinic wax and urea solution.

The paraffinic wax is removed from the system through conduit 20. The urea solution is drawn off through conduit 19 and is transferred to a thickener 26. The excess of urea solvent is evaporated, condensed and recycled to the decomposer 17 through conduit 27.

The urea solution, regenerated in the thickener 26 is admitted into mixer 21 through conduit 28, pre-treated oil from centrifuge 15 also being admitted into mixer 21 through conduit 22. From the mixer 21 the slurry of adduct and oil solution then passes via conduit 23 to the filter 10. The adduct which precipitated as a solid is separated from the solution of dewaxed oil and oil solvent, the adduct being recycled through conduit 11. The solution of oil and oil solvent introduced in the evaporating system 24 is heated to evaporate the oil solvent by means of an evaporator 24 and the finished oil is pumped into a storage vessel or tank 25. The evaporated oil solvent is condensed and recycled through conduit 18 to the washer 16. The wash-filtrate containing some oil is recycled through conduit 29 into the mixer 12.

The quantity of urea passing through the system per cycle is that calculated to react with the paraffinic waxes whose removal is desired, i.e., three times the weight thereof. In the event that the composition of the fresh oil varies, this can be compensated for by changing the rate of introduction of fresh oil and hence of paraffinic waxes, or preferably it is compensated for by either adding further quantities of urea or by removing a portion of the urea solution formed in the decomposer 17.

The process is equally effective using urea for the separation of straight-chain paraffins and their essentially straight-chain derivatives, or using thiourea for the separation of branched-chain paraffins or naphthenes and their derivatives. If desired, heat can be employed to effect the decomposition of the adduct in decomposer 17.

The process may also be effected in a multistage countercurrent operation wherein temperature controls are provided, as shown in Fig. 2. Adduct containing excess urea is introduced from conduit 26 into mixer 27 and there stirred with fresh oil introduced through conduit 28, the fresh oil containing straight-chain paraffinic waxes which it is desired to remove. The contents of the mixer 27 are cooled by evaporation of solvent from the mixer, evaporation being effected by pump 29 which draws off solvent vapors via conduit 30 and introduces the vapors into conduit 37.

The paraffin components exhibiting the greatest affinity for the urea react with the urea until the urea is fully exhausted, the reaction occurring substantially instantaneously. The slurry consisting of adduct and oil solution is conducted via conduit 31 into centrifuge 32 where it is separated into solid adduct and oil, the adduct leaving through conduit 33 while the oil leaves through conduit 34. The adduct is washed in washer 35 and then passes to decomposer 36, in which the adduct is decomposed to paraffinic wax and urea solution.

The paraffinic wax is withdrawn through conduit 38. The urea solution however, is passed through conduit 39 into thickener 50, where the excessive urea solvent is evaporated, condensed and then recycled through conduit 51 to the decomposer 36, while the regenerated urea solution passes to the mixer 45 through conduit 52.

The oil leaving the centrifuge 32 through conduit 34 passes into a second mixer 40 where it is reacted with adduct containing more urea than in the first stage, this

adduct being introduced through conduit 41. The remaining paraffins react with the urea and the slurry is passed through conduit 42 into centrifuge 43. The adduct together with urea and some solvent is separated and returned through conduit 26 to the first mixer 27. The oil passes off through conduit 44 into the third mixer 45 which is also supplied with the regenerated urea solution through conduit 52 leading from the thickener 50.

From the third mixer, wherein the regenerated urea forms an adduct with the residual paraffinic waxes in the oil which has already passed through two treatment stages, the slurry passes through conduit 46 into filter 47. The adduct plus urea which is filtered off together with some adherent urea solvent is passed to the second stage through conduit 41 while the dewaxed oil together with the major portion of the oil solvent pass into evaporator 48 wherein the solvent is distilled off and returned to conduit 37 for use in the washer 35. The oil is then passed to the tank 49.

10 The wash-filtrate containing some oil is passed through conduit 53 to the mixer 27 in order to dilute the fresh oil.

15 The fresh oil was cooled initially but the temperature is allowed to rise freely during the processing so that the oil temperature increases in passing through successive stages. By adjusting the feed rate of the oil and hence of the paraffinic waxes so that the urea is present in the calculated amount ratio per unit of time there will be no deadweight on the process as would otherwise be realized by employing urea in large excess over the amounts required, in an effort to speed up the reaction. In spite of the fact that the feed rate of fresh oil is so great that the rate between paraffin and urea is calculated the reaction rate is not impaired. As a consequence, a greater quantity of oil can be handled in a given apparatus. Moreover, since a large measure of the processing cost involves power expenses for pumping the materials, the fact that urea is not carried through the process as deadweight represents a further and considerable economy.

20 The following examples are illustrative of operations employing the equipment shown in the drawings:

Example I

In a typical run employing the apparatus of Fig. 1, urea was employed for dewaxing a spindle oil of Kuwait origin containing 9.5% by weight of paraffins. To bring the oil to the desired pour point, it was necessary to remove about 90 grams of paraffin wax per liter of oil. The system was operated at a rate such that 30 grams of urea dissolved in water were discharged from the thickener per second. The feed rate was therefore adjusted to 0.11 liters per second, i.e., substantially 3 grams of urea being recycled for each gram of paraffin wax introduced. The paraffin wax was removed in the desired amount when running the apparatus over a period of one hour. The pour point of the raffinate was -20°C .

Example II

The apparatus of Fig. 2 was fed with an oil containing branched-chain paraffins. To obtain the desired pour point it was necessary to remove 18 grams of wax per liter of oil. The process was conducted with thiourea, the regeneration rate of thiourea in the thickener amounting to 30 grams per second, dissolved in water. The feed rate of the oil was therefore adjusted to .55 liter per second. The temperature of the slurry leaving the first mixer was 10°C ., the temperature leaving the second mixer was 18°C ., and the temperature leaving the third mixer was 23°C . The calculated amount of paraffin was recovered per unit of time, the dewaxed oil exhibiting the desired pour point.

Various changes and modifications may be made without departing from the spirit and scope of the present invention and it is intended that such obvious changes and modifications be embraced by the annexed claims.

What is claimed is:

1. The process for the dewaxing of oils comprising the steps of treating an oil in successive stages with a material selected from the group consisting of urea and thiourea at temperatures of between about -10° C. and about $+50^{\circ}$ C., and employing in the last stage a fresh quantity of said material in substantially the amount necessary to remove the desired quantity of paraffinic waxes from the fresh oil introduced in the first stage, said material forming an adduct with some of said paraffinic waxes in each stage, separating the oil from the adduct and any unreacted material in each stage, said adduct in all stages except the first containing unreacted material, passing said adduct with unreacted material in each stage except the first stage to the preceding stage there to be used for dewaxing of the oil, removing the oil dewaxed to the desired degree from the last stage, and removing the adduct from the first stage.

2. The continuous process for the dewaxing of oils comprising the steps of continuously passing an oil through successive stages, treating the oil in each stage with a material selected from the group consisting of urea and thiourea at temperatures of between about -10° C. and about $+50^{\circ}$ C. and employing in the last stage fresh material continuously introduced in substantially 25 the amount per unit of time necessary to remove the desired quantity of paraffinic waxes introduced with the fresh oil in the first stage in said time unit, said ma-

terial in each stage forming an adduct with some of said paraffinic waxes in each stage, continuously separating the adduct and any unreacted material from the oil in each stage, the adduct in all stages except the first 5 containing unreacted material, continuously passing said adduct with unreacted material to the preceding stage there to be used for dewaxing of the oil, continuously removing oil dewaxed to the desired degree from the last stage, continuously removing the adduct from the first stage, continuously decomposing said adduct to regenerate said paraffinic waxes and said material, continuously withdrawing said paraffinic waxes, and continuously recycling said material to said last stage.

3. The process of claim 2, wherein said paraffinic 15 waxes are essentially straight-chain hydrocarbons and derivatives thereof, said material having the formula $\text{CO}(\text{NH}_2)_2$.

4. The process of claim 2, wherein said paraffinic waxes are essentially branched-chain hydrocarbons and derivatives thereof, said material having the formula 20 $\text{CS}(\text{NH}_2)_2$.
